UNITED STATES PATENT OFFICE

WILLIAM F. KIPPLE, OF PORTLAND, OREGON

HAND GRIP BALANCED HOLLOW TILE

Application filed September 25, 1930. Serial No. 484,263.

My invention relates to vertical tiles, comprising interior longitudinal and transverse courses so arranged as to distribute the compression strains; and thus providing a greater load carrying capacity in a tile of normal size; that is, a tile readily handled by the tile layer. Incidentally, I provide a tile readily made and relatively inexpensive to make.

10 Furthermore, my invention has for its object particularly to provide a tile having large air spaces without sacrificing any of its load carrying capacity. Hollow vertical tiles as now made are objectional in that they 15 do not permit the tile layer to pick up and handle the tile with the same facility as he would in ordinary brick.

The reason for this is, the hollow tiles are 20 usually heavier and larger than an ordinary brick. A brick can be readily grasped, picked up and laid with one hand while the other hand holds the trowel. But because of the size and weight of a hollow tile, it can 25 not be picked up with one hand. Two hands are required. A properly made tile should 30 be provided with hand-grip holes of sufficient size, so that the mechanic may readily and conveniently insert the fingers of the hand for grasping interior webs of the tile, and picking it up holding the tile in balance, thus laying the tile with the same facility as he would a brick.

I attain the object of my invention in a 35 vertical hollow tile comprising perimetric, and interior longitudinal and transverse load-supporting, intersecting web-courses, two of the interior medial longitudinal courses being located close together but spaced from the longitudinal middle of the tile, a longitudinal 40 intermediate course being located spaced laterally a substantial distance from each of said medial web-courses, the innermost transverse webs being located relatively close to the ends of the tile, whereby to provide two 45 large air spaces in the middle portion of the tile with said medial longitudinal courses further adapted to facilitate the tile to be firmly grasped by the tile layer, the intermediate web-courses of the tile being located 50 relatively close to its perimetric web courses.

The mechanical advantages gained by my tile construction with regard to the distribution of the compression strains are obvious to anyone versed in the art, from the description above given. Thus I provide a relatively 55 small sized tile, capable of carrying a relatively heavy load, and at the same time providing for large air spaces.

The details of my invention and the features thereof are hereinafter described with 60 reference to the accompanying drawing in which:

Fig. 1 shows a top view, or plan in perspective of a tile embodying my invention; and

Fig. 2 shows a perspective view of my tile, 65 illustrating how the said hand grip holes are adapted to facilitate the grasping, picking up and carrying of the tile by one hand with its weight distributed in balance as 70 mentioned.

The tile *a* may be provided with a plurality of voids as indicated at *b*. In the middle portion of the tile are provided two large air spaces or holes *c*, *c'*. It will be noted 75 that the webs *d* of the tile are arranged so that the weight of the latter is approximately evenly distributed about the point where the hand grasps the tile. Furthermore, the holes *c*, *c'* are arranged parallel with the long side 80 of the tile, thus the tile may be picked up with the left hand of the mechanic inserting the fingers of his hand in the hole *c* and his thumb in the hole *c'*, as illustrated by Fig. 2.

With the tile so held the mechanic positions 85 his arm and holds the tile just the same as he would hold an ordinary brick. His arm will not obscure in any way the line of the wall, thus facilitating the work.

Furthermore, the tile of course must be 90 held horizontal. In other words, parallel with the top surface of the wall, so as to facilitate placing it evenly on the mortar as required. Therefore it is essential that the 95 location of the hand grip holes *c*, *c'* be such that the weight of the web or body of the tile is so evenly distributed that no appreciable muscular effort is required on the part of the 100 mechanic to hold the tile in horizontal posi-

tion. Thus avoiding any muscular strain induced by requiring the mechanic to hold the tile level against any unevenly distributed weight of the tile, which tends to tip the same out of level. With my tile, the mechanic merely picks it up, and its own balanced weight holds it level. The hand grip holes are further so arranged and of ample size as to facilitate the insertion of the hand, and firmly gripping of the tile by the mechanic without hesitancy. Hence he can work just as fast as with ordinary brick.

I claim:

1. A hollow tile comprising perimetric interior, longitudinal, and transverse intersecting web portions, the medial longitudinal web portions spaced close together and the intermediate longitudinal web portions spaced laterally from said medial portions a substantial distance, said transverse web portions being located relatively close to the ends of the tile, whereby to provide two relatively large hand holds between said medial and intermediate longitudinal web courses, such hand holds being located one on each side the longitudinal medial line of the tile.
2. A hollow tile comprising perimetric interior, longitudinal and transverse intersecting web portions, the medial longitudinal web portions spaced close together and the intermediate longitudinal web portions spaced laterally from said medial portions a substantial distance, said transverse web portions being located relatively close to the ends of the tile, thereby to provide two relatively large hand holds between said medial and intermediate longitudinal web courses, such hand holds being located one on each side the longitudinal medial line of the tile, the intermediate web courses of the tile being located relatively close to its perimetric web course.

WILLIAM F. KIPPLE.
